APPARATUS FOR CONTINUOUSLY TREAT-
ING LENGTHY CELLULOSE MATERIAL

Julien Dungler, Basel, Switzerland

Application February 7, 1950, Serial No. 142,773
In France February 16, 1949

1 Claim. (Cl. 34—156)

1

The present invention relates to an apparatus of treating, in particular, of drying cellulose material in bulk and in a continuous manner, namely, paper, cardboard, cellophane and like sheet or hygroscopic web material after an operation involving the wetting of the material (as by printing, coating, impregnating, etc.). More particularly, though not exclusively, the invention is applicable to the drying of paper colored by printing, staining or other process.

It is known that the drying of colored paper encounters difficulties when practiced on a large scale. Thus, where a conventional drier is used wherein the material is simply subjected to an atmosphere of elevated temperature for a certain length of time, the paper displays a tendency to wrinkle over its entire surface and in particular to curl along its edges, especially if the drying is carried out at fairly high speed. In order to avoid these disadvantages, it has heretofore been necessary to dry the paper at a slow rate, involving its remaining in the drying chamber for a considerable length of time.

Accordingly, as a result of this slow rate of drying, it became necessary to use rather bulky equipment if the production was to proceed satisfactorily, and, indeed, in some instances not less than 2,000 meters of paper were engaged by the apparatus at any one time.

A primary object of the present invention is to provide means contributing to an improved treatment of wet cellulose sheets which avoids the above difficulties and disadvantages in an apparatus or machine for carrying such treatment into effect.

More particularly, it is an object of this invention to provide means avoiding undesirable deformation, wrinkling, curling, etc., of wet hygroscopic sheet material while the same is exposed to a treatment fluid.

Another object of the instant invention is to provide means affording rapid drying of colored sheet or sheets of paper or like material in such manner as to brighten the colors thereof and improve the appearance of the finished product.

In order to accomplish the above objects the invention provides, according to one of its aspects, the treatment of a wet hygroscopic sheet by projecting a treatment fluid at high speed upon the surface of the sheet in such manner as to force the same against a support throughout its width.

According to another feature of the invention, the fluid is directed substantially perpendicular, and in a plurality of individual jets or streams, upon the surface of the sheet to be treated while

2

the latter is advanced through the apparatus.

According to a further feature of the invention, the treatment fluid consists, essentially, of superheated vapor and/or steam which may or may not be admixed with air.

According to another object of the invention the apparatus for realizing this treatment comprises a preferably thermally insulated chamber, and means for freely supporting the lengthy strip or web of sheet material as it passes through the chamber, in combination with means for directing streams of treatment fluid upon the surface of the material so as to flatten and straighten the same out against suitable supporting means.

According to a further feature of the invention, the supporting means for the sheet material may be constituted by a plurality of idler rollers.

According to still another feature of the invention, the advance of the sheet material is accomplished by suitable feed means, such as a pick-up device, positioned at one end of the drying chamber therewithout.

According to yet a further feature of the invention, the sheet traverses the chamber twice, on a "forward" and a "return" run, passing both times along the same set of rollers.

These and other objects and features of the invention will become apparent from the following description of a preferred embodiment, reference being had to the accompanying drawing shows somewhat schematically, in longitudinal cross section, an apparatus for drying printed paper in accordance with the invention.

The endless printed paper sheet material 1 emerges from the printing machine, illustrated diagrammatically at 2, and is led over guide rollers 3 with a slight sag as indicated at 1a.

The paper then enters by way of an open end or slot 5 a thermally insulated chamber 4, forming part of the treatment apparatus. Before entering slot 5 the paper has been in contact with guiding and supporting rollers 6.

Inside the chamber 4 the paper travels in substantially taut condition over supporting means, such as a set of parallel and spaced rollers 7 which are freely rotatable about their axes. It will be noted that the paper 1 follows, on its way through the chamber 4, a forward run and a return run, indicated respectively at 1b and 1c, each time moving successively past the same rollers 7.

As the web of paper advances through the chamber 4, the face of the paper runs 1b and 1c bearing the printed stratum is subjected to streams or jets of a drying fluid which is pro-

jected upon the printed paper surface by means of opposite nozzles 8 and 9 defining therebetween a path and positioned close to and at an extremely small distance from the runs 1b and 1c, respectively.

Rollers 7 are positioned in spaced apart relation to each other and within said path between said nozzles 8, 9 in such manner, that a predetermined number of the nozzles are spaced from and disposed intermediate said spaced rollers. Thus, for the runs 1b and 1c, respective passageways are created which extend between rollers 7 and nozzles 8 and rollers 7 and nozzles 9, as clearly seen in the drawing.

The drying fluid is supplied to the nozzles 8 and 9 by means of blower boxes 10 and 11, respectively, communicating with respective blowers 12, 13 the intake ports 14, 15 of which open into the chamber 4, thereby circulating the fluid constituting the atmosphere of the chamber in a closed circuit.

Heating elements 16 and 17, of any suitable type (electric or steam), are provided inside the chamber 4, and positioned as shown, inside the blower boxes 10 and 11, respectively; these heating elements serve to raise the temperature of the drying fluid to the desired degree and to substantially maintain same.

The drying fluid consists preferably, at least in part, of superheated vapor or steam which is admitted into the blower boxes 10 and 11 by way of conduits 18 and 19, respectively.

After the web of paper has traversed the chamber 4 on its forward and return runs, it passes again through the slot 5 where portion 1d is guided over several deflection rollers 20 and finally taken up by collector roll 21. The rotation of this latter roll is preferably synchronized with that of the machine 2, by means shown here diagrammatically as a transmission 22.

The web of paper leaving the printing press 2 is subjected inside the chamber 4 to an extremely rapid and intense drying operation, by virtue of the fact that the drying fluid, or at least a substantial portion thereof, consists of superheated vapor or steam, this drying fluid being forcedly projected against the printed face of the paper 1. Owing to the elevated temperature of the fluid and the high speed of its circulation, the drying process is greatly speeded up, thereby attaining the advantage that the paper remains inside the chamber for a period of time markedly reduced to approximately $\frac{1}{200}$ of that required in known types of driers. Moreover, it has been found that this intense and rapid drying operation also produces a development and brightening of the colors giving the finished paper product a high lustre all its own.

The curling of the edges, so troublesome when the drying is effected in the conventional manner with known equipment, is effectively prevented as the result of the fact that the paper is straightened and flattened against and between the supporting rollers 7, while the jets of fluid are discharged by the nozzles 8 and 9 in the direction of the rollers; furthermore, the speed of the operation likewise contributes to decrease of the tendency of the paper to curl or wrinkle.

The provision of idler rollers 7 to serve as supporting means for the lengthy sheet material 1 simplifies the problem of advancing the paper through the chamber 4 in synchronism with the operation of the printing press 2. The small lengths of the paper portions 1b, 1c, passing at any one time through the chamber 4, makes it

possible to dispense with any positively driven rollers or other feed and supporting means inside the chamber, the paper itself acting as a belt interconnecting the several rollers 7 for simultaneous rotation while bearing freely upon them under the pressure of the jets of the drying fluid. Thus, it is merely necessary to insure synchronization between the printing press 2 and the take-up roll 21, in order to regulate the speed of the paper when passing through the chamber 4 to be equal to the speed at which it leaves the machine 2 (indicated by a constant sag portion 1a). It will, of course, be understood that the transmission 22 may be provided with any known speed changing means (not shown) for accomplishing this result in all instances.

The circulating fluid, after being discharged by the nozzles 8 and 9, acts upon the paper 1 and thereafter mingles with the atmosphere of the chamber 4, whence it is again sucked by the blowers 12 and 13 for recirculation after reheat-ing. Because of the closed circuit thus provided, it is possible to limit the action of the heating elements 16 and 17 so as to produce just enough heat to compensate losses due to radiation or escape of fluid by way of slot 5, in addition to the heat necessary to vaporize the liquid of the wet or fresh print to be removed from the paper. Similarly, the admission of superheated steam through the conduits 18 and 19 may be so adjusted, after the start of the machine and during operation, so as to make up only for any loss caused by leakage.

Before the machine or apparatus is set in motion, the interior of chamber 4 is heated to the desired temperature by means of heaters 16, 17 and introduction of steam through the conduits 18, 19. The excess pressure produced by the influx of steam forces some or all of the air initially present in the chamber to escape through the slot 5. Depending upon the desired operating conditions, substantially all the air may be thus expelled from the chamber 4 before introducing the paper to be dried into the chamber, so that superheated steam alone will constitute the drying fluid, or else a greater or lesser part of the air may be retained, whereby the drying will be effected by a mixture of superheated vapor and air.

It should be understood that the embodiment just described and shown in the drawing has been given merely by way of illustration and not as a limitation upon the scope of the invention which, on the contrary, may be modified in various ways without exceeding its scope. Thus, the shape, character, position and assembly of the elements shown as well as the mode of operation of the apparatus set forth may be altered to suit specific requirements; also, the apparatus may be utilized for treatments other than a drying operation, such as, for example, a polymerization process. It will also be understood that several such processes or treatments may be combined in a single apparatus as, for example, in a waterproofing process.

The idler rollers may likewise be replaced or supplemented by positively driven feed and/or supporting means, e. g. by conveyor belt with perforations, or any other suitable type of support. Also, two or more circulatory systems working in tandem may replace each of the systems 8, 12 and 9, 13 shown in the drawing, if the volume of the chamber would warrant it. Finally, the apparatus illustrated may be combined with auxiliary devices serving, for example, to admit other

treatment media into the chamber, to recover any fluid escaping therefrom, or to evacuate the fluid from the chamber. It is, therefore, intended that all such variations, modifications and adaptations be included within the scope of the appended claim.

It can thus be seen that there has been provided according to this invention an apparatus for treating lengthy, wetted web material, comprising a chamber, a plurality of parallel rollers disposed inside said chamber, the peripheries of said rollers being aligned in two opposite, substantially parallel planes, said planes forming passageways for the forward and the return movement of said material, respectively, feed means for advancing said material through said chamber in contact with said rollers on both of said paths, two sets of nozzles positioned close to said two planes, respectively, and means including said nozzles adapted to discharge a treatment fluid at high speed simultaneously upon a forward traveling and a returning portion of said material, to thereby force said material into close contact with said rollers.

Having thus described the invention, what is claimed as new and desired to be secured by Letters Patent, is:

An apparatus for continuously treating lengthy web material having a wet treated surface; comprising a heating chamber provided with a wall 30 having open slot means, oppositely arranged rows 35 of blowing nozzles in said chamber directing treatment fluid for impingement upon said surface, said rows of nozzles being spaced a predetermined distance from each other to thereby form a treatment path for said material, said nozzles being only spaced an extremely small distance from the material surface when the latter passes through said chamber, to thereby make effective the impingement of said treatment fluid 40 on said surface, exhaust channels arranged intermediate adjacent nozzles of each row of nozzles whereby spent treatment fluid may be withdrawn from said path, a plurality of substantially parallel idler rollers for said material disposed 45

within said path to thereby obtain said distance of said material from said rows of nozzles whereby treatment passageways are defined between one row of said nozzles and one side of said rollers and between the other row of said nozzles and the other side of said rollers, at least some of said rollers being arranged intermediate opposite nozzles, other opposite nozzles being devoid of said rollers and laterally spaced from the latter, said rollers forming guide means for said material whereby said wet treated surface thereof is first exposed to treatment in one of said passageways while said material is being guided from without said chamber through said slot means over said rollers and then exposed to treatment in the other passageway, thence out of said slot means without said chamber, said rollers being adapted to support said material in substantially taut condition when said treatment fluid is directed from said nozzles against said wet treated surface, and feed means without said chamber and adjacent said slot means and adapted to move said material substantially under tension from said slot means of said chamber into the latter and over said sides of said rollers back to said slot means of said chamber for discharge therefrom.
